(57) **CLAIM**

The ornamental design for a toilet flange as shown and described.

DESCRIPTION

FIG. 1 is a front perspective view of a toilet flange according to a first embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is another bottom perspective view thereof;

FIG. 10 is a front perspective view of a toilet flange according to a second embodiment of my new design;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is a bottom perspective view thereof; and,

FIG. 18 is another bottom perspective view thereof.

The broken lines depict portions of the toilet flange that form no part of the claimed design.
